[57] CLAIM

The ornamental design for a headlight louver, substantially as shown and described.

DESCRIPTION

FIG. 1 is a front elevational view of a headlight louver showing my new design;
FIG. 2 is a rear elevational view thereof;
FIG. 3 is a top plan view thereof;
FIG. 4 is a left side elevational view thereof, the right side being a mirror image but for the screw on the bottom of the bezel; and
FIG. 5 is a bottom plan view thereof.
